UNITED STATES PATENT OFFICE.

CHARLES ADAMS, JR., OF WEEHAWKEN, NEW JERSEY, ASSIGNOR OF ONE-HALF TO
SYDNEY F. WESTON, OF NEW YORK, N. Y.

FUSIBLE LINK.

Application filed March 15, 1920. Serial No. 365,843.

To all whom it may concern:

Be it known that I, CHARLES ADAMS, Jr., a citizen of the United States, residing in Weehawken, in the county of Hudson and 5 State of New Jersey, have invented certain new and useful Improvements in Fusible Links, of which the following is a specification.

This invention relates to improvements in 10 fusible links, which, when the temperature reaches a certain predetermined degree, will be automatically released and separated; and is to be used in connection with devices such as automatic sprinkler-nozzles in 15 fire-extinguishing systems, and means for closing fire-doors and shutters, and for similar uses.

One of the main objects of this invention is to provide a fusible-link in which the 20 co-acting locking faces thereof are arranged so as to permit the forming of a fusible stud-member through both co-acting link-members, which fusible element may be headed over, or upset, on both sides of the 25 dual link member when properly assembled, thereby hugging the same together and maintaining the coacting members against disruptive forces until the temperature has risen to a degree sufficient to cause said 30 stud lock member to become fused, thereby releasing the said plates for action in the usual manner.

Another object of the invention is to form 35 a substantial, efficient and effective fusible-link, of simple and light construction but having great holding strength, and in the assembly of which both co-acting members being of duplicate form, a minimum amount of solder will be necessary.

Another object of the invention is to provide 40 a device which will be positive in its action and in which the link members will be readily released, by reason of the fusible solder being melted, when heat to a sufficient degree comes into contact with same.

Other objects of the invention will appear 45 as the description proceeds; and while herein minute details of the invention are described, the invention is not limited to these, since various changes and modifications may be made without departing from the spirit or scope of the invention as claimed.

In the accompanying drawing, showing

by way of example, three of many possible 55 embodiments of the invention;

Figure 1 is a face-view of a fusible link completely assembled, in the preferred form.

Fig. 2 is a side view of such link in central vertical section of Fig. 1, looking from the right.

Fig. 3 is a view in central vertical section of the two parts of such link separated and released one from the other.

Fig. 4 is a view similar to Fig. 2, but on an enlarged scale.

Figs. 5 and 6 are face views of two modifications of the link-members, and

Fig. 7 is a view in central vertical section 70 of the two parts of the link separated and released one from the other, of the modification shown in Fig. 6.

In the preferred form, the fusible-link 75 consists of a pair of mate or duplicate link-members or plates A and A', which link-members are made of some suitable sheet metal, such as manganese bronze of suitable thickness, which are light but very strong and durable as to construction. As these 80 link-members A and A' are of substantially the same size and contour, they can both be made on the same die or punch.

As shown, each of the link-members or plates A and A' has formed therein, at one 85 end, means 1, in the form of an opening or aperture, for engaging the connecting arms B, B, of a spreader valve, not shown, or other device to which the fusible-link may be attached, and at its other end has a cut-away portion 2, so that, when the link-members A and A' are properly assembled, the aperture 1 of each link-member will be oppositely disposed to the cut-away portion 2 of the companion link member.

Each link-member A and A' is provided with an extending locking lug-member or projection 3, as an integral part thereof, which is formed of a hollow cone-like contour with the apex thereof removed, the 100 frustum of said cone-like member received in and against the edges of the opening or aperture 4 of the opposed or companion link member. By reason of the fact that the apex of the cone-like member is removed, it forms an aperture through and 105 through the link-member at the cone-like projection, as shown in Fig. 1. The asso-

ciated aperture 4 is of sufficient diameter to receive the cone-like projection 3, and, after the member or plates AA' are assembled, as shown in Fig. 2, while the outwardly converging sides of the lug member 3 tend to press the plates apart, the headed stud member 5 is so placed as to tie the two link-members together in operative position. The headed stud member 5, as shown 10 in Figs. 2 and 4, is comprised of the usual suitable fusible metal 6, and, in view of the fact that, in the present construction, the composite link is formed of two like members or duplicates, it is therefore obvious 15 that, when they are turned end to end, the associated fusible link-members are held by the two headed-over stud members which are not in shear for the reason that the shearing strains are taken up by the cone-like extensions which are engaged with 20 their associated apertures in opposed links. It will be noted that each stud member 5 constitutes a fusible rivet having in cross-section a wedge shaped body portion which 25 is formed within the lug-member 3, and which co-acting with the heads formed over the ends of the lug member serves to retain the lug-member in engagement in the associated aperture 4, and that upon fusing of 30 the rivet the lug member 3 tends to force the plates apart, there being no solder between the opposed faces of the plates.

In the alternate construction, Fig. 5, there is disclosed a pair of head link members, 35 together with their corresponding apertures, similar to the preferred form shown in Fig. 1, except that instead of being circular, the same are made of oval shape and function in exactly the same manner.

40 In the alternate construction, Fig. 6, there is disclosed a pair of lock or head link members 3 which permit the formation of a stud-like headed over member 5 there-between functioning as above-described, in 45 which the female end 4 of the link has a rectangular opening instead of a round one and the associated protruding member is formed of a pair of integrally mounted outwardly-extending, partly-inclined, lugs or 50 ears, they being so located as to be axially within the line of stress, and by reason of the said inclination of said face, cause ready separation of the links by the camming action of said inclining lugs contacting with 55 said apertures.

There are provided on one surface of the end extensions 7, 7 of the plates AA' projections or bosses 8, 8, and on the opposite surface of the end extensions depressions 8', 60 8', the projections 8, 8 of one plate being of sufficient length when engaged in the depressions 8', 8' of the other plate, and the plates are in face to face assembled relation, to space the plates slightly apart, thereby 65 preventing sliding movement of the plates

and facilitating separation thereof, and when heat is applied to the link to a sufficient degree, the link-members will immediately be released and separated one from the other by reason of the cone-like formation of the locking lug-members 3. 70

I claim:

1. In a fusible-link, a pair of plates, each plate being provided with a lug member and with an aperture therethrough near the lug member; the lug member being open at its base and end and having outwardly converging sides; the plates being arranged in face to face relation to form the link, the lug member of one plate engaging in the aperture of the other plate and tending to press the plates apart; and a rivet of fusible solder passing through the lug member of each plate and the aperture of each plate and having heads formed over the base and over the end 85 of the lug member for retaining the plates in assembled relation. 80

2. In a fusible-link, a pair of plates, each plate being provided with a lug member and with an aperture therethrough near the lug member; the lug member being open at its base and end and having outwardly converging sides; the plates being arranged in face to face relation to form the link, the lug member of one plate engaging in the aperture of the other plate and tending to press the plates apart; a rivet of fusible solder passing through the lug member of each plate and the aperture of each plate and having heads formed over the base and over the end 90 of the lug member for retaining the plates in assembled relation; and means for attachment of the fuse-link to fire-extinguishing apparatus. 95

3. In a fusible-link, a pair of plates, each plate being provided with a lug member and with an aperture therethrough near the lug member; the lug member being open at its base and end and having outwardly converging sides; the plates being arranged in face 100 to face relation to form the link, the lug member of one plate engaging in the aperture of the other plate and tending to press the plates apart; and a rivet of fusible solder passing through the lug member of each plate and the aperture of each plate and having heads formed over the base and over the end 105 of the lug member for retaining the plates in assembled relation; the opposed faces of the plates being free from solder. 110

4. In a fusible link, a pair of plates, each plate being provided with a lug member and with an aperture therethrough near the lug member; the lug member being open at its base and end and having outwardly converging sides; the plates being arranged in face to face relation to form the link, the lug member of one plate engaging in the aperture of the other plate and tending to 125 press the plates apart; and a rivet of fusible 130

solder passing through the lug member of each plate and the aperture of each plate, the body portion of the rivet conforming to the interior of the lug member, and the rivet 5 having heads formed over the base and over the end of the lug member and closing said base and end and the aperture of the plate for retaining the plates in assembled relation.

10 5. In a fusible link, a pair of plates, each plate being provided with a lug member open at each end and having outwardly converging sides, and provided with an aperture through the plate near the lug member; 15 the plates being arranged in face to face relation to form the link, the lug member of one plate engaging in the aperture of the other plate and tending to press the plates apart; and a rivet of fusible solder passing through the lug member of each plate and through the aperture of the other 20 plate, the body portion of the rivet in cross section being of wedge shape and conforming to the converging interior sides of the lug member and the rivet having heads formed over the base and over the end of the 25 lug member and closing said base and end and the aperture of the plate for retaining the plates in assembled relation.

6. In a fusible link, a pair of plates, each 30 plate being provided with a lug member open at its base and end and having out-

wardly converging sides and provided with an aperture through the plate near the lug member, the plates being arranged in face to face relation to form the link, the lug 35 member of one plate engaging in the aperture of the other plate and tending to press the plates apart; and a rivet of fusible solder passing through the lug member of each plate and through the aperture of the other 40 plate, the body portion of the rivet in cross section being of wedge shape and conforming to the converging interior sides of the lug member and the rivet having heads formed over the base and over the end of the 45 lug member and closing said base and end and the aperture of the plate for retaining the plates in assembled relation.

7. In a fusible link, a pair of plates, the plates being arranged in face to face relation to form the fusible link; a truncated cone-shaped member open at its base and end on one plate for engaging an aperture of the other plate at the edge of the aperture, and fusible means passing through said 50 member and aperture for retaining the plates in assembled relation.
